UNITED STATES PATENT OFFICE

SAMUEL NOEL CHEW, OF THORNTON HEATH, ENGLAND, ASSIGNOR TO PNEUMATIC CONVEYANCE & EXTRACTION (1929) LIMITED, OF LONDON, ENGLAND, A COMPANY OF GREAT BRITAIN

DUST SEPARATOR

Application filed August 17, 1926, Serial No. 129,792, and in Great Britain August 19, 1925.

This invention relates to means for extracting dust and grit from air, flue gas or other medium, and more particularly to such means wherein the medium is caused to take a curved path so that the suspended matter, by reason of its greater weight is thrown by centrifugal force to the periphery of the curve.

The object of the invention is to provide improved and simplified construction of apparatus.

According to this invention the extractor comprises a closed casing, forming a collecting chamber for the dust and grit, an outlet at the bottom of the casing and at least one part-circular V-shaped tube in said casing, open at its ends to the surface of the casing and having an outlet opening at its peripheral apex within the casing and inlet opening on its inner side within the casing near its inlet end.

The accompanying drawing illustrates several forms of the invention in which:

Fig. 1 is a side elevation of an extractor 25 with the front side removed.

Fig. 2 is a sectional elevation on line 2, 2

Fig. 1.

Fig. 3 is a plan of a modification.

Fig. 4 is a plan of a further modification 30 showing two curved elements arranged in parallel.

As shown in Figs. 1 and 2, the apparatus comprises a casing *g* in which are mounted two segmental conical discs *c*, *c* arranged to form a circular V-shaped channel. A curved plate *c*¹ extending for the full width of the casing *g* is provided, with the circle of the discs *c* completing the tubular formation of the curved passage. This plate *c*¹ extends 40 to the top of the casing at one end, but at the other end is bent back to leave a gap or passage *f*. Slots *h*, *h* are provided in the edges of the plate *c*¹ between the inner edges of the discs and the side of the casing. Outlet *d* is provided between the contacting edges 45 of the conical discs, suitable guide plates or a chute *e* being arranged therein if desired. Suitably formed inlet and outlet connections *a* and *b* are provided having coupling flanges 50 at each end, the section of the bore of such

connections preferably merging from the circular to the triangular and being curved and set angularly as shown so that they are interchangeable and are directed past one another. The casing *g* is provided at its 55 lower end with the usual inclined bottom, having a suitable outlet *j* for the accumulated dust or other matter.

In operation the dust is driven by centrifugal action to the periphery of the curved 60 V-shaped passage and passes out through the opening *d* the small quantity of air passing through with it returning slowly and almost dust free through the slots *h* and opening *f* to the V-shaped passage where it mingles 65 with the incoming air and is again subjected to centrifugal action.

In the modification shown in Fig. 3, two sets of conical discs *c* are employed forming 70 passages which are connected in series by pipes *k*² and provided with inlet and outlet connections *k*¹ and *k*³ all of which are interchangeable and similar to those shown in Fig. 1.

Fig. 4 shows how the inlet and outlet 75 passages may be arranged for two sets of conical discs *c* connected in parallel that is, two inlets *a* having a common outlet *b*.

In each modification the separating action 80 of the curved passage or passages formed by the cones is similar, the suspended matter being thrown to the outer periphery and passing through a suitable passage or opening with a small quantity of the medium which is subsequently returned at the inlet.

Where desirable the inlet can be made tapered to speed up the gas or other medium in the curved passage, and the dust outlet from the passage may be in the form of a continuous slot, or a series of short slots or holes 90 which may be made by drilling or punching.

In addition to the arrangements shown the cones may be placed at an angle and the crossover pipes or ducts modified so that the path through the apparatus becomes a complete helix.

The construction has amongst other advantages arising out of its improved construction, the feature that owing to the shape of the curved passage the outlet at the periph-

ery may be comparatively small, and the flow of air through such passage may be relatively small and slow.

What I claim is:

- 5 1. An extractor for extracting dust and grit from air or other medium comprising a closed casing forming a collecting chamber for the dust and grit, outlet means at the bottom of the chamber for the collected matter, and a part-circular tube within said casing, for the passage of the medium, of V-shaped section with the apex of the section at its outer periphery, said tube being open at its ends to the outside of the casing for coupling pipes and having two openings within the casing, one an outlet at its peripheral apex and the other an inlet on its inner side near its inlet end, both openings communicating with the collecting chamber, as set forth.
- 10 2. An extractor for extracting dust and grit from air or other medium comprising a closed casing forming a collecting chamber for the dust and grit, outlet means at the bottom of the chamber for the collected matter, and a pair of segmental conical discs in the casing arranged to form the sides of a part circular tube of triangular section, for the passage of the medium, with the apex of its section at its outer periphery, a curved plate-like member coacting with the inner edges of the discs to form the inner face of the said triangular tube, said tube being open at its ends to the outside of the casing for coupling pipes and having two openings within the casing, one an outlet at its peripheral apex between the two discs and the other an inlet on its inner side near its inlet end formed by turning back the end of the curved plate, such curved plate having openings for the passage of the medium from the collecting chamber to such inlet, as set forth.
- 15 30 35 40

In testimony whereof I have signed my name to this specification.

S. NOEL CHEW.
